UNITED STATES PATENT OFFICE.

LEWIS A. PARSONS, OF BROOKLYN, NEW YORK, ASSIGNOR TO THE BROOKLYN WATCH CASE COMPANY, OF SAME PLACE.

DESIGN FOR A WATCH-CASE.

SPECIFICATION forming part of Design No. 18,733, dated November 13, 1888.

Application filed October 6, 1888. Serial No. 287,426. Term of patent 14 years.

To all whom it may concern:

Be it known that I, LEWIS A. PARSONS, a citizen of the United States, residing at Brooklyn, in the county of Kings and State of New York, have invented and produced a new and original Design for Watch-Cases, of which the following is a specification.

The object of this design is to provide a novel and handsome watch-case, as hereinafter described, and illustrated in the accompanying drawing, in which the figure is a side view of a hunting-case stem-winding watch exhibiting the design.

In the drawing, the letter A indicates the watch-case center, made in the form of the frame of a lyre, with the supporting-base B. From the top of the lyre-shaped case-center

projects the pendant C, containing the crown D. The lid E of the watch-case bears, as usual, on the case-center and contains the lyre-strings F.

What I claim is—

The design for a watch-case, consisting of the center A, in the form of the frame of a lyre, provided with a pendant, C, between the arms of the lyre, substantially as shown and described.

In testimony whereof I affix my signature in presence of two witnesses.

LEWIS A. PARSONS.
